(57) CLAIM

The ornamental design for an ice cream container, as shown and described.

DESCRIPTION

FIG. 1 is a top perspective view of a first embodiment of an ice cream container;

FIG. 2 is a front view thereof;

FIG. 3 is a first side view thereof;

FIG. 4 is top view thereof; and

FIG. 5 is a bottom view thereof;

FIG. 6 is a top perspective top view of a second embodiment of the ice cream container;

FIG. 7 is a front view thereof;

FIG. 8 is a first side view thereof;

FIG. 9 is top view thereof; and,

FIG. 10 is a bottom view thereof.

The broken lines shown in the figures are included for the purpose of illustrating portions of the ice cream container and form no part of the claimed design.
